*Primary Examiner—Louis S. Zarfas**Assistant Examiner—Monica A. Weingart**Attorney, Agent, or Firm—Quirk & Tratos***[57] CLAIM**

The ornamental design for a front sight for a firearm, as shown and described.

DESCRIPTION

FIG. 1 is a top-front, perspective view of a front sight for a firearm according to one embodiment of the present invention;

FIG. 2 is a front view of the sight of FIG. 1;
FIG. 3 is a right side view of the sight of FIG. 1;
FIG. 4 is a top view of the sight of FIG. 1;
FIG. 5 is a bottom view of the sight of FIG. 1;
FIG. 6 is a rear view of the sight of FIG. 1;
FIG. 7 is a front view of another embodiment of the sight of the present invention;
FIG. 8 is a right side view of the sight of FIG. 7;
FIG. 9 is a top view of the sight of FIG. 7;
FIG. 10 is a bottom view of the sight of FIG. 7;
FIG. 11 is a rear view of the sight of FIG. 7;
FIG. 12 is a left side view of the sight of FIG. 7;
FIG. 13 is a front view of a sight for a firearm according to another embodiment of the present invention;
FIG. 14 is a right side view of the sight of FIG. 13;
FIG. 15 is a top view of the sight of FIG. 13;
FIG. 16 is a bottom view of the sight of FIG. 13;
FIG. 17 is a rear view of the sight of FIG. 13;
FIG. 18 is a left side view of the sight of FIG. 13;
FIG. 19 is a front view of a sight for a firearm according to another embodiment of the present invention;
FIG. 20 is a right side view of the sight of FIG. 19;
FIG. 21 is a top view of the sight of FIG. 19;
FIG. 22 is a bottom view of the sight of FIG. 19;
FIG. 23 is a rear view of the sight of FIG. 23; and,
FIG. 24 is a left side view of the sight of FIG. 19.

The broken line showing of a gun barrel in FIG. 1, an extension in FIGS. 4-6, 8-12, 14-18, 20-22, and 24, and a pivot in FIG. 13, is for illustrative purposes only and forms no part of the claimed design.
